CLAIM

The ornamental design for a display screen with graphical user interface, as shown and described.

DESCRIPTION

FIG. 1 is a front view of a display screen with graphical user interface my new design; and,

FIG. 2 is another view thereof, showing alternate graphic elements which form no part of the claimed design. The outermost broken line showing an electronic device illustrates environmental subject matter, and forms no part of the claimed design. The inner broken rectangle showing the display screen and remaining broken lines showing elements of the graphical user interface illustrate portions of the article, and form no part of the claimed design.

1 Claim, 2 Drawing Sheets
